ABSTRACT: A warm air producing unit in which an airflow chamber and a tank for the bulk storage of liquid are both heated by a common combustion chamber is characterized in that part of the surface area of the tank is exposed directly to the heat generated in the combustion chamber so that the water in the tank may be heated, and part of the surface area of the tank is swept over by at least some of the airflow in the airflow chamber, the ratio of the two areas being such that when the combustion gases have heated the water in the tank to a predetermined temperature the heat loss from the contents of the tank to said airflow is sufficient to prevent said predetermined temperature from being exceeded.

PATENTED FEB 16 1971

3,563,225

WARM AIR UNITS

BACKGROUND OF THE INVENTION

1. Field of the Invention

This invention relates to warm air developing units of the kind in which a blower causes air to flow through one or more airflow chambers heated by a combustion chamber, the resulting warm air being used to heat buildings.

2. Description of the Prior Art

Prior warm air developing units have been constructed to include a tank for the bulk storage of liquid but such constructions have suffered from one or both of the following drawbacks: (1) not enough hot water is readily available to meet normal domestic requirements; (2) if sufficient hot water is not drawn off within a predetermined period, the water in the tank commences to boil.

This invention eliminates the above drawbacks by providing a combined warm air developing unit and bulk liquid storage tank in association with a common combustion chamber in such a manner that an adequate supply of hot water is always readily available but such that the water in the tank will not boil.

SUMMARY OF THE INVENTION

The warm air developing unit disclosed herein comprises a combustion chamber, one or more airflow chambers through which an airflow can be created, and a tank for storing a bulk supply of liquid, characterized in that part of the surface area of the tank is exposed directly to the heat generated in the combustion chamber so that water in the tank may be heated, and part of the surface area of the tank is swept over by at least some of said airflow, the ratio of said areas being such that when the combustion gases have heated the water in the tank to a predetermined temperature the heat loss from the contents of the tank to said airflow is sufficient to prevent said predetermined temperature from being exceeded.

To ensure an adequate supply of warm air, one or more of said airflow chambers have surfaces exposed directly to the heat generated in the combustion chamber.

Thus, the general principle of the present invention is that a bulk hot water tank, for example of galvanized metal, is built into a combustion chamber of the warm air unit, and at least part of the walls of this bulk storage unit is protected by at least one of the aforesaid airflow chambers. The surface area of the walls of the water tank that are permitted to be heated directly by the burning gases in the combustion chamber; and the surface area of the walls of the water tank that are shielded by said airflow chamber; are so related that a careful balance is maintained between the flow of burning gases over the water tank and flow of hot air over the water tank, to ensure that the water in the water tank shall be capable of reaching, but not exceeding, a predetermined maximum temperature whilst the warm air blower is operating and the combustion chamber is in operation.

The storage capacity of the tank and area of the tank that is exposed directly to the heat generated in the combustion chamber are such as to provide a supply of hot water sufficient to meet the demands of a predetermined domestic requirement.

There may be two airflow chambers arranged one inside the other, such that there is a space between said airflow chambers through which the combustion gases can flow to heat air passing through said airflow chambers. In this construction the inner wall of the inner airflow chamber surrounds some of the water in said tank.

The two airflow chambers may each be of annular shape, the inner wall of the inner airflow chamber having upper and lower closures such that at least some of said inner wall and said upper and lower closures cooperate to define said tank. In this construction it is the lower closure of the tank that may be exposed directly to the heat generated in the combustion chamber.

The outer airflow chamber may also surround the combustion chamber.

The combustion chamber may be of the flame rim type, that is to say a combustion chamber that utilizes a horizontal ring of grilles or walls onto which fuel is sprayed, there being means to ignite fuel vapors rising from fuel sprayed onto said ring. The diameter of the ring is preferably less than the diameter of the inner wall of the outer annular airflow chamber and greater than the diameter of the outer wall of the inner annular airflow chamber, with the ring being disposed below the tank.

DESCRIPTION OF THE DRAWING

15 The drawings show a schematic cross-sectional view through one embodiment of a warm air developing unit incorporating a tank for the bulk storage of liquid.

DESCRIPTION OF THE PREFERRED EMBODIMENT

20 As shown the warm air unit comprises a combustion chamber 1 in which is a flame rim 2. The burning gases 2A rising from the flame rim 2 pass up an annular-flue flow path 3 defined by an outer wall 3A and a further wall 3B and escape via a stack 4.

25 The annular-flue flow path 3 surrounds an annular airflow chamber 5 to which air is supplied at the lower end chamber 5 defined by the outer wall 3A and an inner annual wall 5A and air is supplied at the lower end of chamber 5 by ducting 6. The air in the chamber 5 is heated by the burning or burnt gases 2A passing up the annular flow path 3 and eventually escapes via an outlet 7 where the heated air is distributed through suitable ducting (not shown) to the point where hot air is required.

30 According to the invention the annular airflow chamber 5 surrounds the inner wall 5A which forms the vertical sides of a hot water tank 8, the tank 8 has an upper transversely extending wall 8A and a lower transversely extending wall 8B or base tank 8 being of sufficient volume to accommodate a bulk

35 supply of hot water, for example 15 to 30 gallons depending upon the size of the warm air unit. It will be understood from the drawing that the lower wall 8B or base of the hot water tank 8 is exposed to the combustion gases in the combustion chamber 1, but that the inner wall 5A which forms the side walls of the water tank 8 are swept over by the air being drawn through the airflow chamber 5.

40 By suitably proportioning the surface area of the water tank 8 that is exposed to the combustion chamber 1 as compared with the surface area of the water tank 8 that is surrounded by the annular air flow chamber 5 containing air to be heated, it is possible to predetermine the maximum temperature to which the water in the storage tank is capable of being raised under normal operating conditions, for example 90° C. Thus, when cold water is present in the tank 8, it receives heat not only from the direct action of the combustion gases on the louver wall 8B of the water tank 8, but it receives heat also from the hot air circulating through the annular airflow chamber 5 and against the inner wall 5A thereof, thus ensuring a rapid rise in temperature of the water in the water tank 8.

45 When the temperature of the water in the tank 8 commences to rise above the temperature of the air flowing through the airflow chamber 5, then the water in the tank 8 commences to give up some of its heat to the air flowing through the airflow chamber 5. Thus, eventually, a static state is reached at which the exchange of heat from the water in the tank 8 to the air flowing through the annular airflow chamber 5 is equal to the rate at which heat is being transmitted to the water via the lower wall 8B of the water tank 8. When this occurs the water

50 in the tank 8 is at the aforesaid predetermined maximum temperature.

55 To ensure maximum efficiency of the warm air unit an outer annular airflow chamber 9 defined by a casing 9A surrounds the flow path 3 for the burning or burnt gases. Thus, the burning or burnt gases passing up the flow path 3 transmit heat to

both the chamber 5 and the chamber 9, both chambers receiving air at their lower ends by means of a blower 11 mounted at the base of the unit and passing hot air out via exits 7 and 10 respectively. The blower 11 is illustrated as being below the combustion chamber.

The efficiency of the air heating unit is enhanced by having the flame rim 2 of such size that the flames rising therefrom are adjacent to the inner wall of the outer airflow chamber 9.

The water tank 8 may be fitted with an electrical immersion heater for use during the summer months and may be so wired electrically that it is impossible for said immersion heater to be energized when the flame rim 2 is in operation.

Having now described one embodiment of the present invention it will be appreciated that the combustion chamber 1 may be fired by any suitable means and that said means is not necessarily the aforesaid flame rim 2.

It will also be appreciated that whereas in the particular embodiment illustrated, only the base of the water tank 8 is exposed to the combustion gases and the remainder of the water tank 8 is screened by the airflow chamber 5, this is by way of example only and any other suitable surface areas may be so heated and screened in order to achieve the desired maximum temperature of the water in the water tank 8 under normal operating conditions of the warm air unit.

Thus, whilst only one particular embodiment of the present invention has been illustrated and described, it will be apparent to those skilled in the art that various changes and modifications may be made therein without departing from the spirit of the invention, and having thus described my invention.

I claim:

1. A warm air developing unit comprising inner and outer

walls defining between them an upwardly extending annular-shaped airflow passage, the inner wall of said airflow passage having spaced apart transversely extending upper and lower walls defining between them in association with said inner wall

5 a tank for storing a bulk supply of water, a further wall defining a combustion chamber surrounding said outer wall and depending below said lower transversely extending wall such that the combustion gases generated below said lower transversely extending wall can act directly on said lower transversely extending wall, the space between said outer wall and said further wall acting as a flow path for the combustion gases around the annular-shaped airflow passage, air inlet ducting passing through said further wall to the airflow passage, and an air outlet opening in the unit permitting air to escape from the 10 upper end of said airflow passage, the surface area of the tank that is surrounded by said airflow passage being such that when the water in the tank has been heated to a predetermined temperature by the combustion gases the heat loss from the water in the tank to the air flowing through said airflow 15 passage is sufficient to prevent said predetermined temperature from being exceeded.

2. A warm air developing unit as claimed in claim 1 and including an upwardly extending outer casing surrounding and spaced from said further wall to form a further airflow 20 passage.

3. A warm air developing unit as claimed in claim 2 and wherein said air inlet ducting passes through said further wall to communicate with said further airflow passage.

4. A warm air unit as claimed in claim 2 and wherein the air 30 outlet opening receives air from the airflow passage and the further airflow passage.
